APRON

Ada Quinn, Ogden, Utah

Application August 4, 1939, Serial No. 288,444

6 Claims. (Cl. 2—48)

This invention relates to aprons for personal wear, and more particularly to women's aprons of the sleeveless type employing either shoulder straps or a yoke, a back section or panel, and tie members connected to the side edges of the apron for cooperation with the back section in securing the garment in proper position upon the body of the wearer.

One of the objects of the invention is to provide an apron of this general character which is not only relatively inexpensive to manufacture and economical in the amount of material used, but is also easily donned and removed, neat and attractive in appearance, and capable of being worn by and properly fitted to persons of different heights and sizes.

Since the invention is particularly directed to the structure of the back of the apron, another object is to provide a new and improved back construction employing novel means for forming the openings through which the tie members may be passed so as to adjust and fit the apron to the body of the wearer.

Another object is to simplify the back construction of an apron of this character without detracting from the ability of the construction to effect proper adjustment and fitting of the apron.

These and other objects will appear more fully upon a consideration of the two forms of apron which have been described and illustrated in the accompanying drawing, although it is to be expressly understood that this drawing is for the purpose of illustration only and is not to be construed as defining the limits of the invention, reference being had to the appended claims for this latter purpose.

In the drawing, wherein like reference numerals indicate like parts throughout the several views:

40 Fig. 1 is a back view of one form of apron embodying the invention wherein the back section or panel is formed as the lower end of a substantially V-shaped member which is in turn made integrally with or suitably connected to the shoulder straps;

45 Fig. 2 is a view of the back construction of Fig. 1 detached from the remainder of the apron and showing the panel in unfinished condition to better illustrate the way in which the tie member receiving openings are formed;

50 Fig. 3 is a back view similar to Fig. 1 showing another embodiment of the invention wherein the back section or panel depends from a neck yoke and the tie member receiving loops are

formed in a different manner than in Figs. 1 and 2; and

5 Fig. 4 is an enlarged cross sectional view of the lower end of the back section of Fig. 3 illustrating in detail the way in which the tie member receiving loops are formed.

Referring first to Figs. 1 and 2, the apron shown therein consists essentially of a body portion 11, a pair of shoulder straps 12 each attached at one end to the upper edge of the body portion 11, a V-shaped back 13 either formed integrally with or suitably connected to the shoulder straps 12 at its upper extremities and of sufficiently wide material to form a shaped back section or panel 14 at its lower end adjacent the 10 waistline, and a pair of tie members 15 suitably secured to the side edges of the body portion 11 at about the waistline and adapted to be selectively passed through suitable openings or loops 15 associated with the section 14 when adjusting 20 and securing the apron in place on the body of the wearer.

In this first embodiment of the invention, the back section 14 has secured to its lower end a strap or tape 16 of fabric material, and is provided intermediate its upper and lower ends with a pair of strap or tape receiving openings 17 disposed in vertically spaced, closely adjacent relationship. The strap or tape 16 is adapted to be threaded upwardly through the two openings 25 17 and to then have its upper end suitably secured, as by stitching 18, to the upper edge of the section 14 which, in the embodiment illustrated, is the point of junction of the inner edges of the two sides of the V-shaped back 13. In 30 this manner, there are formed a plurality of vertically spaced loops or openings arranged in a single line through which the tie members 15 may be selectively passed when adjusting and securing the apron in place upon the body of the 35 wearer. That is, in fitting the apron to a person of any given size, the front or body portion 11 is first adjusted upwardly or downwardly by lowering or raising the back section 14 which lies substantially in the small of the back, after which 40 the tie members 15 are passed through whichever of the loops or openings formed by the strap 16 lies closest to the waistline, the tie members being 45 passed under the strap 16 as indicated in Fig. 1 and then suitably secured together, as by a 50 bow overlying said strap.

In the modified construction of Figs. 3 and 4, the back section or panel 19 is substantially rectangular in shape and is secured at its upper end to a split neck yoke 20, instead of to the shoulder 55

straps 12. The loop forming strap or tape 21 of this modification is approximately twice as long as that of Figs. 1 and 2, and the panel 19 is provided with a third opening 22, spaced vertically above the pair of openings 23 corresponding to those indicated at 17 in Figs. 1 and 2 by a distance equal to the height of the tie member receiving loop or opening which it is desired to form, the free end of the strap 21, after being threaded through openings 23, then passing through opening 22 and returning behind the back panel to the lower edge thereof where it is secured in any suitable manner, as by stitching.

There is thus provided by the present invention an apron of new and improved construction which is comparatively cheap to manufacture as to both material and labor costs, and which may be readily adjusted to persons of different sizes without detracting from its smooth-fitting qualities and attractiveness. Due to the novel construction and arrangement of the parts forming the apron back, a plurality of vertically disposed tie member receiving openings may be provided in a simple and expeditious manner so as to facilitate the proper adjustment and fitting of the apron to the body of the wearer. The constructions illustrated provide an extremely simple and effective way of forming tie member receiving loops or openings which will not pull out during use. The apron may also be conveniently washed and ironed flat, thus facilitating folding and storage of the laundered garment. These and other features which will be apparent from the foregoing description render the garment of the present invention especially well adapted for use in factories, hospitals, hotels and other institutions where aprons are used in large quantities by persons of various sizes, and where a neat and attractive appearance is required.

Although two different forms of apron back construction have been described and illustrated in the accompanying drawing, it will be obvious that the invention is not limited to the exact structures shown but is capable of a variety of mechanical embodiments. For example, the exact shape and size of the back section or panel and the manner of its attachment to the rest of the apron may be varied from those illustrated, and the number of tie member receiving loops or openings in the single vertical series provided may be increased beyond two, if so desired. It will also be recognized that the aprons may be made up in various shapes, colors and styles, from various materials and goods, and with or without ornamental features and finish which it is unnecessary to show in the drawing. Various other changes, which will now appear obvious to those skilled in the art, may be made in the form, details of construction and arrangement of the parts without departing from the spirit of the invention. Reference is therefore to be had to the appended claims for a definition of the limits of the invention.

What is claimed is:

1. In an apron of the type wherein a pair of tie members are secured to the side edges of the body portion of the apron adjacent the waistline, a back section operatively connected at its upper end with the body portion of the apron, and means associated with said back section forming a plurality of tie member receiving openings disposed in a single vertical line, said means consisting of a strap of fabric material secured to said section at its extremities only, the portion

of said strap intermediate its extremities being threaded through a plurality of vertically spaced openings in said section and freely slidable through said openings to form loops of adjustable size through which the tie members may be selectively passed when adjusting and securing the apron in place upon the body of the wearer. 5

2. In an apron of the type wherein a pair of tie members are secured to the side edges of the body portion of the apron adjacent the waistline, a back section operatively connected at its upper end with the body portion of the apron, and means associated with said back section forming a plurality of tie member receiving openings disposed in spaced apart relation in a single vertical line, said means consisting of a strap of fabric material secured at its ends only to said section and threaded intermediate its ends through at least one pair of vertically arranged openings formed in said section, the portion of 10 said strap extending between said openings lying behind the section, the other portions thereof lying in front of said section and forming loops through which the tie members may be selectively passed when adjusting and securing the apron in 15 place upon the body of the wearer. 20

3. In an apron of the type wherein a pair of tie members are secured to the side edges of the body portion of the apron adjacent the waistline, a back section operatively connected at its upper end with the body portion of the apron, and means associated with said back section forming a plurality of tie member receiving openings disposed in spaced apart relation in a single vertical line, said means consisting of a strap of fabric material sewn at one end to the lower edge of said section, having its bight passing freely through an opening in said section and the portion thereof between said bight and its opposite end extending downwardly behind the 30 section to the lower edge thereof where said opposite end is also secured, the portion of said strap between said first mentioned end and said bight being threaded and freely slidable through at least one pair of closely adjacent, vertically 35 spaced openings in said section so as to provide a plurality of loops of adjustable size through which the tie members may be selectively passed when adjusting and securing the apron in place upon the body of the wearer. 40

4. A back section for an apron of the sleeveless type employing a pair of tie members secured to the side edges of the apron for cooperation with the back section in adjusting and securing the apron in place upon the body of the 45 wearer, consisting of a piece of fabric material of substantial area, a strap of fabric material secured to said section at its extremities only, and a plurality of vertically spaced openings in said section through which said strap is threaded 50 to form a plurality of vertically arranged loops through which said tie members may be selectively passed when adjusting and securing the apron in place upon the body of the wearer, the portion of said strap intermediate its extremities 55 being freely slidable through said openings to vary the relative sizes of said loops and thereby facilitate passage of the tie members through the loop selected for use. 60

5. In an apron of the type wherein a pair of 70 tie members are secured to the side edges of the body portion of the apron adjacent the waistline, a back panel having a permanent connection with the remainder of the apron adjacent the neck and shoulder level, and means asso- 75

ciated with said back panel forming a plurality of tie member receiving openings disposed in spaced apart relation in a single vertical line, said means consisting of a strap secured at its 5 ends to the upper and lower edges of said panel, and at least one pair of vertically separated openings in said panel through which the portion of said strap intermediate its ends is threaded and freely slideable so as to form a plurality of loops 10 of adjustable size through which the tie members may be selectively passed when adjusting and securing the apron in place upon the body of the wearer.

6. In an apron of the type wherein a pair of tie members are secured to the side edges of the 15

body portion of the apron adjacent the waistline, a back panel having a permanent connection with the remainder of the apron adjacent the neck and shoulder level, and means associated with said back panel forming a plurality 5 of tie member receiving openings disposed in spaced apart relation in a single vertical line, said means consisting of a strap sewn at both ends to the lower edge of said panel but on opposite sides of the latter, and a plurality of vertically separated openings formed in said panel through which the bight of said strap is threaded and freely slideable when fitting and adjusting the apron to the body of the wearer.

ADA QUINN. 15
